UNITED STATES PATENT OFFICE.

CHARLES I. E. MASTIN, OF MIDLAND PARK, NEW JERSEY.

PISTON-PACKING.

1,209,740.

Specification of Letters Patent. Patented Dec. 26, 1916.

Application filed October 6, 1915. Serial No. 54,291.

To all whom it may concern:

Be it known that I, CHARLES I. E. MASTIN, a citizen of the United States, and resident of Midland Park, county of Bergen, and State of New Jersey, have invented certain new and useful Improvements in Piston-Packing, of which the following is a specification.

This invention relates to a packing for piston rods and other moving parts of engines and machinery where a tight joint is required to prevent the passage of steam or other fluid under pressure.

One of the main objects of the invention is to provide a packing of simple construction which would be durable and especially adapted for use under high pressures and high temperatures.

Another object of the invention is to provide a packing containing lead inserts, and to so secure the lead inserts in the packing that all danger of separation of the lead from the fibrous and rubber portions of the packing is avoided.

Another object of the invention is to so arrange the lead inserts that they will form a practically continuous annular line of contact between the lead and the moving part to be packed.

Another object of the invention is to provide corrugated lead inserts which are individually and independently wrapped with a suitable number of layers of rubber-coated fabric and then combined in the packing, the said wrapped inserts being permanently secured between a suitable number of flat layers of rubber-coated fabric.

Another object of the invention is to provide a packing having lead inserts, with an air cushion whereby said packing will be rendered flexible and yielding to the desired degree.

There are other objects and advantages of the invention which will appear hereinafter.

In the drawing, Figure 1 is a perspective view of a packing strip constructed in accordance with my invention; Fig. 2 a similar view of a packing strip, the air cushion and the fabric inclosing and binding strip being

omitted; Fig. 3 a transverse sectional view of the lead inserts with their individual wrapping strips as they are arranged before being compressed in the completed packing strip; Fig. 4 a transverse sectional view of the strip as shown in Fig. 2, with a binding strip applied; Fig. 5 a detail view of a portion of the bias-cut fabric which is wound around the metal inserts; and Fig. 6 a similar view of a part of the bias-cut rubber-coated fabric of which the flat layers of the packing are formed.

The lead inserts 1 are corrugated as shown in Figs. 1 and 4, and each insert is individually wrapped with a suitable number of layers of rubber-coated fabric 2. These wrapped inserts are assembled, as shown in Fig. 3, and placed between a suitable number of flat layers of rubber-coated fabric 3. These assembled parts are then subjected to pressure to thoroughly unite all of the rubber parts and to form the packing into a substantially homogeneous mass, as shown in Fig. 2. The layers of fabric around the lead inserts are distorted and compressed sufficiently to reduce the entire packing to a substantially solid mass without air spaces. The lead inserts are preferably arranged in the completed packing as indicated in Figs. 1 and 2 so that there will be a slight overlap between adjoining inserts. The object of this arrangement of the inserts is to provide a substantially continuous line of bearing between the lead and the rod or other part to be packed. By individually wrapping each corrugated lead insert they will be permanently anchored in the packing and it will be impossible for them to become loosened in use. The wrappings of rubber-coated fabric will become thoroughly interlocked with the corrugated lead inserts when the packing strip is subjected to pressure as described. When the packing has been brought to the condition described it is in what is termed the "green" state, the rubber being then in a sticky or gum-like condition, sufficiently adhesive to hold the parts in their compressed condition. If it is desired that the lead inserts shall be exposed upon the inner and outer surfaces of

the completed packing, the packing strip in this "green" condition is bent into ring or spiral form and finally cured by heat and pressure.

5 In some forms of the packing, the strip is provided with a covering or binding strip 4, as shown in Fig. 4. This binding strip is preferably placed on the packing while it is in its "green" state, the covered packing 10 being then placed in a suitable mold in which it is compressed and subjected to heat to permanently cure or vulcanize it into its finished state. The binding strip 4 may be formed of one or more thicknesses as desired. The strip 4 is preferably placed over the two flat sides of the packing formed by the layers 3, and over that edge of the packing which will be the outer surface when the strip is coiled or formed into 15 rings. It is obvious that when this binding strip is used the ends of the lead inserts are exposed only upon the inner or wearing face of the packing.

When it is desired to form a packing 20 which is more flexible than the strip shown in Fig. 4, a rubber core 5 having a longitudinally extending aperture 6, is placed back of the packing strip made up as shown in Fig. 2, and the whole then inclosed in a binding strip 7 as shown in Fig. 1. The completed strip, including the core and the binding strip, is then placed in a mold in which it is subjected to pressure and heat 25 to cure or vulcanize the gum and rubber core and to fix the entire packing strip in its permanently cured condition. It is obvious that the inclosing or binding strip 7 may be of one or more thicknesses as desired. This binding strip extends over the two flat sides 30 of the packing strip and also over the outer side thereof, or that portion of the packing which will be the outer side when the packing is coiled or formed into rings.

The fabric 2 in which the lead inserts are 35 wrapped, is cut on the bias so that the ends only of the threads are exposed at the ends of the lead inserts. The fabric layers 3 between which the wrapped lead inserts are placed, is also cut on the bias and arranged 40 in the packing strip so that the ends only of the threads are exposed upon the wearing face of the packing. By this arrangement the ends only of all the threads of the fabric used in the packing are exposed on 45 the wearing face of the packing. The advantage of this construction will be obvious to those skilled in the art. It is obvious that the inserts 1 may be made of any suitable metal.

50 From the foregoing it is obvious that I provide a packing in which the lead inserts will be securely anchored and will not work loose or become detached when the packing is in use. It is also obvious that a packing

constructed as described herein will be especially adapted for use in high fluid pressures and high temperatures; and that the rubber core with the aperture therethrough will form a yielding backing for the main body of the packing which will render the 70 same flexible and permit it to readily adapt itself to unevenness in the travel of the packed rod or other moving part.

What I claim is:

1. A packing strip comprising metal in- 75 inserts, rubber-coated fabric wrapped around said inserts, and layers of rubber-coated fabric covering the wrapped metal inserts, the ends of said inserts being exposed upon the wearing face of the packing.

2. A packing strip comprising corrugated metal inserts, rubber-coated fabric wrapped around each of said inserts, and rubber-coated fabric layers forming the flat surfaces of the packing, the individually wrapped metal inserts lying between said fabric layers, and the ends of the metal inserts being exposed at the wearing face of the packing.

3. A packing comprising metal inserts, 90 rubber-coated fabric wrapped around each of said inserts, and flat layers of rubber-coated fabric, the metal inserts and their wrappings being arranged in a mass between said flat fabric layers, the ends of 95 the metal inserts being exposed upon the wearing face of the packing.

4. A packing comprising metal inserts, rubber-coated fabric inclosing said inserts and separating them from each other, the 100 said inserts being arranged to provide a substantially continuous metal bearing surface around the part packed, and layers of rubber-coated fabric forming the flat surfaces of the packing, the inclosed inserts 105 lying between said layers of rubber-coated fabric, the ends of the inserts being exposed on the wearing face of the packing.

5. A packing comprising corrugated metal inserts, rubber-coated fabric wrapped 110 around each of said inserts, said wrapped inserts being arranged in a mass, rubber-coated fabric layers forming the flat sides of the packing and between which the mass of wrapped inserts is fixed, a hollow rubber 115 core along the outer surface of the packing forming a cushion, and a binding strip of fabric covering the flat sides of the packing and inclosing the rubber core, the ends of the inserts being exposed upon the wear- 120 ing face of the packing.

6. A packing comprising metal inserts, bias-cut rubber-coated fabric wrapping for each insert, and means for holding said inserts in a mass, whereby the ends of the 125 threads of the fabric wrappings will be exposed at the ends of the inserts.

7. A packing comprising metal inserts,

bias-cut rubber-coated fabric wrapped about each of said inserts, the said inserts being arranged in a mass, bias-cut rubber-coated fabric layers forming the flat sides of the packing, the mass of wrapped inserts lying between said fabric layers, whereby the ends

of all the threads of the fabric in the packing will be exposed on the wearing face of the packing.

In testimony whereof I hereunto affix my 10
signature.

CHARLES I. E. MASTIN.
